UNITED STATES PATENT OFFICE.

SAMUEL A. KREWSON, OF MERCHANTVILLE, NEW JERSEY, ASSIGNOR, BY DIRECT AND
MESNE ASSIGNMENTS, TO LOUIS G. FREEMAN, OF CINCINNATI, OHIO

SHOE-TRIMMING MACHINE.

933,651.

Specification of Letters Patent. Patented Sept. 7, 1909.

Application filed March 12, 1906. Serial No. 305,645.

To all whom it may concern:

Be it known that I, SAMUEL A. KREWSON, a citizen of the United States, and a resident of Merchantville, New Jersey, have invented certain Improvements in Shoe-Trimming Machines, of which the following is a specification:

My invention relates to machines employed for the purpose of trimming or rounding the soles of shoes, especially that portion directly underlying the heel, preparatory to securing the heel tap to such soles.

The object of my invention is to provide simple and effective means for doing this work, in operating which I am enabled to utilize the heel portion of the shoe in which the last is inclosed as the gage or guide for the counter of the cut.

My invention is fully shown in the accompanying drawings, in which:

Figure 1, is a sectional elevation of the sole trimming machine, made in accordance with my invention; Fig. 2, is a plan view 25 of a part of the same; Fig. 3, is a view illustrating the manner of operating the machine; Figs. 4 and 5, are diagram views of a shoe heel, one showing the sole before trimming, and the other showing such sole 30 after it has been trimmed; Figs. 6 and 7, are views of details of my invention, and Fig. 8, is a view illustrating a modification of my invention.

The principal object of my invention is to insure that the contour of the sole at the heel portion, which serves afterward as a guide for the heel, shall be in line with and equidistant at all points from the curved surface of the heel.

In the drawings herewith, 1 represents a feed wheel at the front of the machine, between which and a guiding wheel 2, the edge 3 of the shoe sole to be cut away is introduced, in the manner clearly shown in Fig. 3. Situated at the proper point with relation to these members and having its cutting edge in line with the axis of rotation of the feed wheel and guide wheel, is a knife 4 to cut away or trim the excess portion of the sole. Both wheels are vertically movable to permit the introduction of the sole between the same, and the shoe is held by the operator with the last pressed against the guiding wheel 2. The shoe is turned 55 around by the operator as the cutting opera-

tion progresses so as to sever the excess portion of leather from the sole with a contour the same as the heel portion of the shoe.

The guiding wheel 2 is recessed at 2^a to facilitate the positioning of the knife 4 and said wheel 2 held in position with respect to the feed wheel 1, by means of set screws 7 and 8. This wheel 2 is carried by a shaft 9 journaled in a sleeve 10 pivotally supported by a lever 11 pivoted at 12 and carrying set screws 13 and 14, which are employed to adjust and restrict the movement of the same. This lever has a handle 15 whereby said guiding wheel may be raised to permit the entrance of the work between said guiding 70 and feed wheels.

The feed wheel is carried by a shaft 16 journaled in bearings 17 and 18, the latter being guided at the front of the machine by projections 19, and the former being pivotally mounted at the rear of the machine so that a rocking movement on said pivots may be imparted to said shaft. Power to drive this shaft is imparted by means of a worm 21 carried by a shaft 22, which also carries a pulley 23 by which power may be applied from a belt, such worm meshing with a worm wheel 24 on the shaft 16. This shaft also carries a pinion 26 near its forward end which meshes with a pinion 27 carried by 85 the shaft 9 supporting the guiding wheel.

The shaft 16 is supported at its forward end by a spring 30 carried by the lever 11, and having its opposite end connected to a sleeve 31 through which the shaft 16 passes. A foot treadle (not shown) may be connected to a wire rod 32 surrounding said shaft 16, and by this means said shaft may be lowered against the action of the spring 30 to introduce the work between the wheels. 90 Tension is applied to said spring by a thumbscrew 33.

The knife 4 is carried by a plate 35 adjustable so as to take up the wear on the cutting edge of the same and insure that said edge is always in line with the axis of rotation of the guiding and feed wheels. The guide wheel is preferably polished, and the operator in removing the excess of the material holds the shoe against said wheel and turns it so that the cutting edge is in line with the center of rotation or movement of the shoe in the hands of the operator. The width of cut may be determined by the guiding wheel which may be adjustable back 105 and forth.

and forth and held in the adjusted position by suitable means as shown in Fig. 6; or guide wheels of varied thickness may be employed as shown in Fig. 7. As a further means of providing for such adjustment of the shoe and regulating the cut, I mount a shelf 36 at the front of the machine upon which the operator may rest the sole of the shoe. This shelf is hinged at 37 and lies at an angle with respect to the contacting surfaces of the two rolls; being adjustably held in the raised or lowered positions by set screws 38. This structure serves to vary the angle at which the cut is made, and thereby regulates the width of the material left on the shoe.

In addition to the usefulness of my machine for trimming the soles of shoes, it may be employed as a randing machine. In Fig. 8, I have shown a rand cutting knife 39 disposed beneath the guiding wheel 2, and having its cutting edge in line with the center of rotation of said wheel. This figure also shows a section of a shoe in position for the knife to remove the rand from the edge of the sole.

By preference the operating and adjustable parts of the machine are inclosed by the casing 40.

30 I claim:—

1. The combination, in a sole trimming machine, of a feed wheel, means for driving the same, a guide wheel for the work having an edge to engage the sole being trimmed and a face for engagement by the body of the shoe carrying such sole whereby the sole may be trimmed to the same contour as said body, means for driving said guide wheel from the means for driving the feed wheel, independently operated means for imparting vertical movement to both of said wheels, and a knife blade having its broad face at right angles to the axis of rotation of said wheels and its cutting edge in line with such axis.

2. The combination, in a sole trimming machine, of a feed wheel, means for driving the same, a guide-wheel having an edge to engage the sole being trimmed and a face for engagement by the body of the shoe carrying such sole whereby the sole may be trimmed to the same contour as said body, means for driving said wheel from the means for driving the feed wheel, a knife disposed behind and having its cutting edge in line with the axis of rotation of said wheels, independent means for imparting vertical movement to the carriers for both of said wheels to permit insertion of the work, and adjustable means for maintaining said carriers for the wheels in the proper relative positions.

3. In a sole trimming machine, the combination of a feed wheel, a shaft pivotally hung for carrying the same, means for driving said shaft, a guiding wheel, a shaft

carrying said wheel, a pivotally mounted support for said wheel, means whereby said guiding wheel is driven from the feed wheel shaft, means connecting the support for said guiding wheel to the feed wheel shaft, and a knife disposed behind and having its cutting edge in line with the axis of rotation of said wheels.

4. In a sole trimming machine, the combination of a feed wheel, a shaft pivotally hung for carrying the same, means for driving said shaft, a guiding wheel, a shaft carrying said wheel, means whereby said guiding wheel is driven from the feed wheel shaft, a pivotally mounted support for said guiding wheel shaft, means for adjustably mounting the guiding wheel shaft in said support, means for adjusting said support, a knife coacting with said wheels, and means connecting the support for said guiding wheel shaft to the feed wheel shaft.

5. The combination, in a sole trimming machine, of a frame, a feed wheel for the work, a guide wheel for the work, supporting means for said wheels carried by said frame, means for driving said wheels in unison, the guide wheel being driven from the feed wheel driving means, means for imparting vertical movement to each of said wheels independently of each other, and a knife disposed below the guide wheel and having its cutting edge in line with the center of rotation of said wheels and lying across the space between the peripheral edges of said wheels to engage the sole moved thereby.

6. The combination, in a sole trimming machine, of a frame, a feed wheel carried thereby, a shaft therefor pivotally supported in said frame, means for driving said shaft, means for imparting independent vertical movement to the end of said shaft, a guide wheel, a shaft carrying the same, gearing to drive said guide wheel from the feed wheel shaft, adjustable means for supporting said guide wheel shaft whereby the guide wheel may be moved vertically away from the feed wheel, resilient means connecting the support for said guide wheel to the feed wheel shaft, and a knife disposed behind said wheels and having its cutting edge in line with the axis of rotation of the same.

7. The combination, in a sole trimming machine, of a frame, a feed wheel carried thereby, a shaft therefor supported by said frame, means for driving said shaft, means for supporting said shaft in such position as to permit independent vertical movement of the same, a guide wheel, a shaft carrying the same, means whereby said guide wheel is driven from the feed wheel shaft, a lever for supporting said guide wheel shaft whereby said guide wheel may be moved vertically away from the feed wheel, means carried by said lever for limiting its movement, means

connecting the support for said guide wheel to the feed wheel shaft, and a knife disposed behind said wheels and having its cutting edge in line with the axis of rotation of the 5 same.

8. The combination, in a sole trimming machine, of a frame, a feed wheel carried thereby, a shaft therefor supported by said frame, means for driving said shaft, means 10 for supporting said shaft in such position as to permit independent vertical movement of the same, a guide wheel, a shaft carrying the same, means whereby said guide wheel is driven from the feed wheel shaft, a lever 15 pivotally mounted in said frame for supporting said guide wheel shaft whereby said

guide wheel may be moved vertically away from the feed wheel, means carried by said lever for limiting its movement, means also carried thereby for adjusting the position of 20 the guide wheel shaft, means connecting the support for said guide wheel to the feed wheel shaft, and a knife disposed behind said wheels and having its cutting edge in line with the axis of rotation of the same. 25

In testimony whereof, I have signed my name to this specification, in the presence of two subscribing witnesses.

SAMUEL A. KREWSON.
